(57) **CLAIM**

I claim the ornamental design for a reinforced steel stud, as shown and described.

DESCRIPTION

FIG. 1 is a perspective view of a reinforced steel stud, showing my new design;

FIG. 2 is a front elevational view thereof;

FIG. 3 is a rear elevational view thereof;

FIG. 4 is a top plan view thereof, the bottom plan view being a mirror image thereof; and,

FIG. 5 is a left-side elevational view thereof, the right-side elevational view being a mirror image thereof.

The broken lines in FIGS. 1-4 are included for the purpose of illustrating the indeterminate length of the design.
